UNITED STATES PATENT OFFICE.

HARLAND FANKBONER, OF CHICAGO, ILLINOIS, ASSIGNOR TO THE GOSS PRINTING PRESS COMPANY, OF CHICAGO, ILLINOIS, A CORPORATION OF ILLINOIS.

PRINTING-PRESS.

1,257,834.

Specification of Letters Patent. Patented Feb. 26, 1918.

Application filed June 12, 1917. Serial No. 174,374.

To all whom it may concern:

Be it known that I, HARLAND FANKBONER, a citizen of the United States, and a resident of Chicago, in the county of Cook and State 5 of Illinois, have invented certain new and useful Improvements in Printing-Presses, of which the following is a specification, reference being had to the accompanying drawings.

10 My invention relates to printing presses comprising form cylinders equipped with clamping devices movable for securing the forms on the cylinder. It is one of the principal objects of my invention to provide a new and improved form and arrangement of parts by reason of which the press is rendered incapable of being started normally into operation while a printing plate is in position upon the cylinder and not locked 15 up normally into position thereon but which will at the same time permit the press to be started and normally operated whether or not the plate-clamping mechanism is in locked up condition when there is no printing plate in position on the cylinder. It is another object of my invention to provide an arrangement of parts of this improved type by reason of which the presence of a clamp-operating tool upon the cylinder will 20 prevent the normal starting of the press. It is still another object of my invention to improve mechanisms of this type in sundry details hereinafter pointed out. The preferred means by which I have accomplished my 25 several objects are illustrated in the accompanying drawings and are hereinafter specifically described. That which I believe to be new and desire to cover by this application is set forth in the claims.

30 In the drawings:

Figure 1 is a side view, partially in vertical section, showing the preferred embodiment of my invention in a cylinder of a printing press.

35 Fig. 2 is a similar view, but showing the parts in a changed position.

Fig. 3 is a top or plan view showing the parts in the position illustrated in Fig. 2.

40 Fig. 4 is a vertical cross section taken substantially on line 4—4 of Fig. 3.

Fig. 5 is an enlarged detail, being substantially a section taken on line 5—5 in Fig. 2.

45 Referring to the several figures of the

drawings, in which corresponding parts are 55 indicated by the same reference characters,—

10 indicates a plate cylinder revolubly supported in position upon a heavy shaft 11 mounted in suitable bearings on a framework 12. The cylinder 10 has slidably 60 mounted upon it at each end portion two heads 13—14, each of which is adapted to be locked in position and held against movement longitudinally of the cylinder by means of an eccentric member 15 revolubly 65 mounted in an enlarged central portion 16 of such head. The eccentric 15 is adapted to be turned by means of a suitable tool inserted in an angular socket 17 in its outer end portion, suitable means of any appropriate type being provided for holding the member 15 against rotating except when the tool is in position in the socket, all as is well understood in the art.

Each of the heads 13—14 is provided 75 with a plurality of longitudinally-extending screws 18 revolubly mounted therein, such screws in turn being provided with plate-clamps 19 of any suitable type adjustably secured in position thereon by means of 80 screw-threads. As is fully understood in the art, when the heads 13—14 are moved toward the right in Fig. 1 by a suitable partial rotation of the eccentric 15, the clamps 19 are moved also toward the right for engaging the edge of a plate 20 in position on the cylinder. As is fully understood in the art, the plate-clamps 19 are adapted to be adjusted longitudinally of the cylinder to any desired position relative to the heads 85 13—14 by suitable rotary adjustment of the screws 18. In the construction shown in Fig. 1, the cylinder 10 is a type adapted to receive four or more printing plates longitudinally thereof, the inner edge of the plate 90 20 being in engagement with a plurality of plate-clamps 21 which are slidably mounted in the cylinder, such clamps 21 being in engagement at their opposite sides with another printing plate 22.

100 My improved construction comprises a shield or guard 23 pivotally mounted upon a yoke 24 carried by the framework 12. This guard 23 comprises a circumferentially-extending portion 25 adapted to overlie the 105 socket 17 of the eccentric member 15, as is shown in Fig. 3, and another portion 26 extending transversely across the outer face

of the head 13—14. The shield or guard is provided at one side of the cylinder with an arm 27, the outer end portion of which carries the movable member of an electric switch of any suitable type, the arrangement of the parts as shown in the drawings being such that upon a movement of the guard out of normal position an electric circuit is broken for rendering the press-driving means inoperative. In this construction as shown, the switch comprises a block 28 of any suitable insulating material secured upon the arm 27, such block 28 being provided with a suitable contact member 29 normally held by means of a spring 30, spaced a short distance above the block. The stationary members of the switch in the construction shown comprise contact members 31—32 which are connected respectively with the wires 33—34 of a controller circuit of any suitable type by which the operation of the press is regulated, the driving means being rendered inoperative, in the construction shown, by the breaking of the circuit through the switch. The arm 27 is normally held in position by a spring 35 for keeping the circuit closed through the switch.

My improved construction comprises further an arm 36 pivotally mounted on each of the heads 13—14 on its outer face near its edge in such position as to stand opposite the portion 26 of the guard or shield 23 when the cylinder 10 is in normal position to receive a printing plate to be clamped thereon. In the construction shown, the portion of the arm 36 which extends outwardly beyond the pivotal axis of the arm is offset relative to the portion extending inwardly, but it will be understood that this offset feature is not necessary to an operative embodiment. The inwardly-extending portion of the arm 36 is provided with an opening 37 through which a longitudinally-extending rod or link 38 passes, said rod or link being provided with a head 39 on its outer end. The rod or link 38 has pivotally connected to it bellcrank levers 40—41 pivotally mounted on the cylinder within suitable openings 42 therein. As is best shown in Fig. 1, the turned ends of the horizontally-extending arms of said bellcrank levers are adapted to be engaged by printing plates in position upon the cylinder, such as the plates 20—22 as shown in the drawings, the engagement of the printing plates with the levers serving to hold the rod or link 38 against movement toward the left in Fig. 1 beyond the position shown therein.

As will be readily appreciated upon an examination of the several figures, whenever a tool is in position in the socket 17 of the eccentric member 15, with the cylinder 10 in normal position to receive a printing plate, such tool by its engagement with the portion 25 of the guard or shield 23 will serve to

hold said guard out of normal position against the action of the spring 35 and serve thus to hold the switch open for preventing the operation of the press, whether or not a plate is in position upon the cylinder and whether the head 13—14 is in plate-locking position or out of plate-locking position. Whenever there is no tool in position in the socket 17, however, and no printing plate in position upon the cylinder, the guard or shield 23 is adapted to stand in normal position as shown in Fig. 1 whether the head 13—14 is in plate-locking position or out of plate-locking position. In that case, with the head 13 in the position shown in Fig. 2, and with the plates 20 and 22 removed from the cylinder 10, the spring 35 will hold the shield or guard 23 in normal position as shown in Fig. 1, the rod or link 38 being adapted to move toward the left in Fig. 2, by reason of the absence of the printing plates, so as to permit the arm 36 to swing in clockwise direction from the position shown in Fig. 2, it being understood that the spring 35 is of sufficient strength to insure the switch being held closed when no printing plate is in position upon the cylinder. On the other hand, when there is no tool in position in the socket 17 of the eccentric but there is a plate in position upon the cylinder 10, the guard or shield 23 will be in normal position for permitting the operation of the press if the head 13—14 is in plate-locking position and will be out of normal position serving to prevent the operation of the press if the head 13—14 is out of plate-locking position. This result is attained by virtue of the fact that the head 39 of the rod or link 38 is located in such position upon such rod or link that, when the head 13—14 with the arm 36 thereon and the plate clamps carried thereby is standing at the limit of its movement toward the left in Figs. 1 and 2 while the rod 38 is standing at the limit of its necessary movement toward the right in said figures by reason of the presence of a printing plate upon the cylinder, the head 39 engages the inwardly-extending portion of said arm so as to hold the arm and the guard or shield 23 turned in counterclockwise direction in Fig. 2 against the action of the spring 35, serving thus to hold the switch open for preventing the operation of the press.

So far as I am aware, I am the first in the art to provide a form and arrangement of parts by reason of which a printing press is rendered incapable of being operated normally when a printing plate is in position on the plate cylinder of the press with the plate-locking means in inoperative position while at the same time permitting the normal operation of the press when no plate is in position on the cylinder regardless of whether or not the plate-clamping means is locked up, and by claims are to be construed ac-

cordingly. This novel arrangement permits normal running of the press with a portion only of the cylinder equipment of the press provided with printing plates without its being necessary for the pressman to take the precaution of first locking up all the plate-clamping mechanisms of that part of the press not to be provided with printing plates. I am thus enabled to

10 provide proper safety devices for the part of the press in use without in any way increasing the labor of the pressman or the responsibility of the pressman in relation to the part of the press not in use.

15 I have shown in the drawings only a fragmentary portion of the means for driving the press,—namely, the small portion of the controller circuit which can be thrown into and out of operation by the manipulation of 20 the switch as above described,—but it will be understood that this driving means may be of any approved type and it is therefore believed to be unnecessary to show in detail any complete driving system.

25 What I claim as my invention and desire to secure by Letters Patent is,—

1. In a printing press, the combination of a plate cylinder, clamping means movably mounted on said cylinder for locking a 30 printing plate in position thereon, and means held in position by a printing plate on said cylinder for preventing the normal operation of the press while the plate-clamping means is out of plate-locking position.

35 2. In a printing press, the combination of a plate cylinder, clamping means movably mounted on said cylinder for locking a printing plate in position thereon, means held in position by a printing plate on said cylinder for preventing the normal operation of the press while the plate-clamping means is out of plate-locking position, and other means coöperating therewith for preventing the normal operation of the press while a 40 clamp-operating tool is in position on the cylinder.

45 3. In a printing press, the combination of a plate cylinder, clamping means adjustably mounted on said cylinder for locking a printing plate in position thereon, means adapted to be moved into position to prevent normal driving of the press, and means held in position by a printing plate on the cylinder adapted when the plate-clamping means is 50 out of operative plate-locking position to engage said movable means for holding it in position for preventing operation of the press.

55 4. In a printing press, the combination of a plate cylinder, clamping means slidably mounted on said cylinder for locking a printing plate in position thereon, means adapted to be moved into position to prevent normal driving of the press, and means adapted 60 when no plate is in position on the cylinder

to stand out of engagement with said movable means so as to permit normal operation of the press but adapted when the plate-clamping means is out of operative plate-locking position to be held by a printing 70 plate upon the cylinder in position to engage said movable means for holding the same in effective position for preventing operation of the press.

5. In a printing press, the combination of 75 a plate cylinder, clamping means movably mounted on said cylinder for locking a printing plate in position thereon, means for driving the press, and means held in effective position by a printing plate upon said cylinder 80 for throwing said driving means out of operation.

6. In a printing press, the combination of a plate cylinder, clamping means movably mounted on said cylinder for locking a 85 printing plate in position thereon, means for driving the printing press, and means adapted to have no effect upon said driving means when no plate is in position upon said cylinder but adapted when a plate is 90 in position upon said cylinder to prevent operation of the press by said driving means except when the plate-clamping means is in operative plate-clamping position.

7. In a printing press, the combination of 95 a plate cylinder, clamping means movably mounted on said cylinder for locking a printing plate in position thereon, electrically operated means for driving said press, comprising a switch by the operation of which said driving means may be thrown out of operation, and means held in effective position by a printing plate upon said cylinder for effecting an operation of said switch.

8. In a printing press, the combination of 100 a plate cylinder, clamping means movably mounted on said cylinder for locking a printing plate in position thereon, and means movably mounted on said cylinder and adapted to move freely out of operative 105 position when there is no plate upon said cylinder but adapted to be held in operative position by a plate on the cylinder for preventing the normal operation of the press while the plate-clamping means is out of 110 plate-locking position.

9. In a printing press, the combination of a plate cylinder, clamping means movably mounted on said cylinder for locking a plurality of printing plates in position thereon, 120 and devices movably mounted on said cylinder opposite the several positions for plates on said cylinder adapted to move freely out of operative position when there is no plate on the cylinder but adapted to be held in 125 operative position by a plate thereon for preventing the normal operation of the press while the plate-clamping means is out of plate-clamping position.

10. In a printing press, the combination of 130

- a plate cylinder, clamping means movably mounted on said cylinder for locking a printing plate in position thereon, a bellcrank lever pivotally mounted on said cylinder adapted to be engaged by a plate in operative position on said cylinder, a rod slidably mounted on said cylinder and connected with said bellcrank lever, an arm pivotally mounted on said cylinder adapted to be engaged by said rod and displaced from normal position thereby when a plate is in position in engagement with said bellcrank lever and with the plate-clamping means out of operative plate-locking position, and means actuated by the displacement of said arm for preventing the normal operation of the press.
11. In a printing press, the combination of a cylinder, a head slidably mounted on said cylinder and movable longitudinally into and out of operative position, clamping means movable longitudinally of said cylinder with said head into and out of plate-clamping position, a bellcrank lever pivotally mounted on said cylinder adapted to be engaged by a printing plate in operative position on said cylinder, a rod slidably mounted on said cylinder and operatively connected with said bellcrank lever, an arm pivotally mounted on said head adapted to be engaged by said rod and displaced thereby from normal position when a plate is in

position in engagement with said bellcrank lever and with said head out of operative position on the cylinder, and means actuated by the displacement of said arm for preventing the normal operation of the press. 35

12. In a printing press, the combination of a plate cylinder, clamping means movably mounted on said cylinder for locking a printing plate in position thereon, means for driving the press, means held in effective position by a printing plate upon said cylinder for throwing said driving means out of operation, and other means coöperating therewith for preventing normal operation of said driving means while a clamp-operating tool is in position on the cylinder. 40 45

13. In a printing press, the combination of a plate cylinder, clamping means slidably mounted on said cylinder for locking a printing plate in position thereon, electrically-operated means for driving said press, comprising a switch by the operation of which said driving means may be thrown out of operation, means held in effective position by a printing plate upon said cylinder for effecting an operation of said switch, and other means coöperating therewith for holding said switch open so long as a clamp-operating tool is kept in position on said cylinder. 50 55 60

HARLAND FANKBONER.
